UNITED STATES PATENT OFFICE.

JULIUS J. MILLER, OF ST. JOSEPH, MICHIGAN, ASSIGNOR TO WILLIAM P. HEALY, OF CHICAGO,
ILLINOIS.

WIRE-BOUND BOX.

No. 887,337.

Specification of Letters Patent.

Patented May 12, 1908.

Application filed April 30, 1906. Serial No. 314,373.

To all whom it may concern:

Be it known that I, JULIUS J. MILLER, a citizen of the United States of America, and resident of St. Joseph, Michigan, have invented a certain new and useful Improvement 5 in Wire-Bound Boxes, of which the following is a specification.

My invention relates to boxes provided with binding wires which are twisted together when the box is closed—that is to say, which extend around the box and have their end portions twisted together to hold the box in closed condition.

The object of my invention is to provide 15 a box of this character with means for twisting and covering the ends of the wire when the box is closed. In this way, I not only prevent the wire ends from becoming untwisted, but I also prevent such ends 20 from injuring the hands of freight handlers.

To the foregoing and other useful ends, my invention consists in matters herein-after set forth and claimed.

In the accompanying drawings, Figure 1 25 shows the box open. Fig. 2 shows the box, closed. Fig. 3 is an enlarged detail perspective view of one corner of the box. Fig. 4 is an enlarged front view of the twister applied to the wire ends. Fig. 5 is 30 a front view of the twister. Fig. 6 is a back view of the twister. Fig. 7 is a top edge view of the twister. Fig. 8 is an enlarged section on line 8—8 in Fig. 4. Fig. 9 shows the wire end crossed and bent and ready to 35 receive the twister.

As thus illustrated, my invention comprises the side and bottom walls 1, 2 and 3, and the swinging top wall or cover 4. The walls are connected together by the outside 40 binding wires 5, 6 and 7 and reinforced by the inside cleats 8. Staples are used to secure the binding wires and cleats to the veneer of which said walls are composed. End walls or heads 9, 10 are secured to the cleats 45 at points inside the same, to close the ends of the box. When the box is closed, as shown in Fig. 2, the tapered twistlers A are applied to the wire ends to twist the same together and cover the sharp or dangerous 50 ends thereof. Each twister is made of sheet metal and provided with rolled or curled edges a—a providing tubular or round sockets for the wire ends, so that each fits

snugly but removably therein. These curled or rolled-over edges converge downwardly 55 and meet at the apex or lower end of the twister, providing sockets which lie at an angle to each other—that is to say, sockets the mouths of which face away from each other in opposite or different directions. 60 When the box is closed, the wire ends are crossed and bent together, as shown in Fig. 9. Then the twistlers are slipped onto the end portions of the wires, and each twister is then turned so as to twist together the wire 65 ends, as shown in Fig. 4. As the wire ends converge, the twistlers cannot fall off, and, in fact, cannot be dislodged until they are forcibly pulled off to open the box. As the 70 said sockets or holes for the wires are obstructed or closed at their outer ends, the ends of the wires cannot protrude therefrom. With the wire ends thus covered, they cannot injure the hands of freight 75 handlers. While they are not liable to come off, each twister is nevertheless removable in the sense that it can be removed or slipped off when the box is to be opened.

It will be seen that the twistlers A are adapted to increase the tension of the binding 80 wires of the box, by using said twistlers like thumb pieces for rotating and twisting together the ends of the binding wires. In this way each twister is applied to the free 85 end portions of the wire, and the wire is then given a double spiral twist between the twister and the main portions of the wire.

It will be seen that the spiral twist of each binding wire is disposed between the twister A and the body or encircling portion of the 90 wire. In other words, the twist does not constitute a part of the means for encircling the box, but to the contrary projects laterally therefrom. In this way the twister is not subject to the tension which is given the wire 95 to cause it to embrace the box. For this reason the twister itself does not constitute any portion of the medium by which the box is encircled or embraced. It will be seen that the twisting together of the ends of the 100 wire serves to grip the combined twister and guard, as the wires are bent sharply and pull at an angle to the sockets, when the twist becomes tight, as shown in Fig. 4. The un-twisting, by rotating the twister and guard 105 in the opposite direction, then serves to un-

lock the twister and guard, as the wires spread apart, so that the twister and guard is then easily removed.

What I claim as my invention is:

- 5 1. As a new article of manufacture, a combined twister and guard for the adjoining ends of a binding wire consisting of an approximately triangular plate having two of its opposite edges each curled to form a 10 tubular socket, said sockets being open at their inner ends and closed at their convergent or outer ends, for the purpose set forth.
- 15 2. The combination of a box bound with a wire the adjoining free ends of which are twisted together, as and for the purpose set forth, and a twister and guard consisting of a metal plate having tubular sockets open at their inner ends and closed at their outer 20 ends, these sockets receiving and inclosing the sharp ends of the wire beyond the twist and lying at an angle to each other.
- 20 3. A box bound with a wire the adjoining free ends of which are twisted together, pro-

vided with a twister and guard consisting of 25 a metal plate having tubular sockets open at their inner ends and closed at their outer ends, these sockets receiving and inclosing the sharp ends of the wire beyond the twist and converging toward their outer ends, 30 substantially as disclosed.

4. A box bound with a wire the free end portions of which are twisted together, provided with a combined guard and twister consisting of an approximately triangular 35 piece of sheet metal having each of two of its edges curled into a tube open at its inner end, these tubes converging toward their outer ends and inclosing the entire outer end portions of the wire beyond the twist, as set 40 forth.

Signed by me at St. Joseph, Berrien county, Mich., this 26th day of April, 1906.

JULIUS J. MILLER.
